UNITED STATES PATENT OFFICE.

SYVER LOE, OF MINNEAPOLIS, MINNESOTA.

VOTING-MACHINE.

SPECIFICATION forming part of Letters Patent No. 712,079, dated October 28, 1902.

Application filed February 14, 1902. Serial No. 94,008. (No model.)

To all whom it may concern:

Be it known that I, SYVER LOE, a citizen of the United States, residing at Minneapolis, in the county of Hennepin and State of Minnesota, have invented certain new and useful Improvements in Voting-Machines; and I do hereby declare the following to be a full, clear, and exact description of the invention, such as will enable others skilled in the art to which it appertains to make and use the same.

My present invention relates to voting-machines, and has for its object to improve the same in the several particulars hereinafter noted.

The invention consists of the novel devices and combinations of devices hereinafter described, and defined in the claims.

Certain of the features illustrated in the present case are disclosed and broadly claimed in my prior patents, Nos. 688,533 and 688,534, both of date December 10, 1901, and both entitled "Voting-machine."

A machine embodying the several features of my invention is illustrated in the accompanying drawings, wherein like characters indicate like parts throughout the several views.

My present invention is especially directed to the provision of an improved limiting-lock or vote-limiting mechanism; but it involves other novel features and combinations of parts, all of which will be hereinafter pointed out, and defined in the claims.

Figure 1 is a plan view with some parts broken away, showing a voting-machine embodying the several features of my invention and showing the parts in their normal positions. Fig. 2 is a view corresponding to Fig. 1, but showing the parts moved into their set positions. Fig. 3 is a front elevation of the machine, some parts being broken away and others being shown in section. Fig. 4 is a detail view, principally in side elevation, looking at the machine from the left and showing the limiting-lock or vote-limiting mechanism, some parts being broken away and others being shown in section. Fig. 5 is a detail of one of the elements of the vote-limiting mechanism. Fig. 6 is a detail in section illustrating principally the independent - vote-controlling device, and Fig. 7 is a detail in section substantially on the line $x^1 x^2$ of Fig. 2.

The numeral 1 indicates a rectangular skeleton frame or support, suitably supported at

its base or lower end by feet or other devices. 55
(Not shown.)

The numeral 2 indicates a vertically-disposed fulcrum-shaft, suitably secured at its ends to the skeleton heads of the frame 1. Register-actuating levers or keys 3 are pivoted on this fulcrum-shaft 2 in horizontal positions one over the other. Projecting finger-pieces 4 of said levers work outward through suitable passages in the front of the frame 1. Said levers are further provided 65 with toothed segments 5 and with projections 6, having lugs or shoulders 7 and 8, all for purposes which will presently appear. Each lever 3 carries a sliding latch 9, secured thereto by slot-and-pin connections 10 and provided at its projecting end with a reversely-beveled or approximately V-shaped cam-nose 11. The cam noses or ends 11 of the latches 9 all work with a camming action against a vertically-disposed cam-rod 12, rigidly secured at its ends to the heads of the frame 1. Said latches 9 are yieldingly forced against the rod 12 by springs 13, shown as connected to the rear ends thereof and the fulcrum-rod 2. With this construction it is evident that 70 by the coöperation of the cam-noses 11 of the latches 9 with the cam-rod 12 under the action of the springs 13 the actuating-levers 3 will be yieldingly held in either of the two 75 positions indicated in Figs. 1 and 2 in which 80 they may be set.

In my present machine, as well as in my said prior machine, the actuating levers or keys are arranged in groups and appropriated one to each candidate for a particular office 90 to which the group is appropriated. For each actuator there is a register, and for each group of actuators and registers there is a limiting-lock or vote-limiting mechanism, one element of which is subject to each actuator and which group serves to limit the 95 number of votes which may be cast for the particular office to which the group is appropriated.

The numeral 14 indicates as an entirety 100 one of the registers or recording-tallies, which registers are, as shown, suitably secured in a vertical stack located at the forward left-hand corner of the frame 1, as shown in the drawings. As shown, each register involves 105 three numeral-wheels, the unit member of which is provided with ratchet-teeth 15. The carrying devices for the register-wheels are

not shown, but may be of any suitable or well-known construction.

To each lever or key 3 is pivotally connected a register-actuating pawl 16, the projecting toothed end 17 of which is adapted to engage the teeth 15 of the coöperating register. At their intermediate portions the pawls 16 are provided with longitudinal slots 18, through which extend the eccentric portions 19 of a vertically-disposed rock-shaft 20, the ends of which are journaled in brackets 21, secured on the main frame 1. To the lower end of the rock-shaft 20 is secured an arm 22, to which connects a link 23.

15 In the vicinity of the beveled ends 11 of the lever-latches 9 is a vertically-disposed restoring-blade 24, provided with trunnions 25, suitably journaled in bearings 26 on the frame 1. To the lower trunnion of this restoring-blade 24 three arms 27, 28, and 29 are secured, and to the upper trunnion of said blade is secured an upper arm 29, which is a mate to the said lower arm 29. The arm 27 is connected to the link 23, while the long 25 arm 28 is pivoted to a plunger or slide 30, provided at its projecting end with a handpiece 31. Said arm 28 is also pivotally connected to another plunger or slide 32, which works outward through a slot 33 in one of 30 the rear bars of the frame 1 and is provided with a handpiece 34. The said plunger 32 is also provided at one side with an abrupt locking-shoulder 35 and with a beveled shoulder 36. A spring 37 presses laterally on the plunger 32 and causes one or the other of the 35 said shoulders 35 and 36 to normally maintain engagement with the said slot 33.

We will now consider the most important feature of my invention—to wit, the limiting-lock or vote-limiting mechanism.

38 indicates a vertically-disposed non-rotary shaft supported at its upper and lower ends by the heads of the frame 1. This shaft 38 is provided with a key 39, which runs from 45 end to end thereof. Mounted to slide in said shaft 28, but held against rotation thereon by said key 39, is a series of screw-threaded hubs 40, on each of which is mounted with screw-threaded engagement a spur-pinion 41. 50 Mounted on the shaft 38 between the sliding hubs 40 are sliding washers 42. Each pinion 41 meshes with one of the toothed segments 5 of the actuating-levers 3, and it will be noted that said pinions have very wide faces 55 as compared with the said segments, so as to permit the gears to move laterally to a very considerable extent while in mesh with the coöperating segments. The pinions 41 act as nuts. The sliding hubs and gears are separated into groups by detachable and adjustable stop-brackets 43, shown as secured to a vertical base 44 of the frame 1 by screws 45. The bar 44 is shown as provided with screw-holes 46, so spaced that the said brackets 60 43 may be applied between any two pinions and to any washer 42. The stop-brackets 43 are provided with projecting prongs 47, the

ends of which are notched and are adapted to be interlocked with perforations 48 in a vertical guide-plate 49, which plate 49 is 70 suitably secured to the frame 1. Said plate 49 is also provided with slots 50, through which the segmental ends of the actuating levers or keys 3 freely work and by which they are held against lateral movements. 75 The crotches afforded by the prongs 47 are grooved, so as to embrace and tightly hold the washers 42, to which the brackets 43 are applied. To more rigidly connect the stop-brackets 43 against lateral springing movements, I provide a long screw-threaded rod 51, which is suitably anchored at its ends and is provided with nuts 52 to clamp the said brackets 43. The brackets 43 are provided with open notches to receive the rod 85 51 and to permit the same to be readily detached therefrom by sidewise movement.

It will be noted that the screw-threaded hubs 40 and the pinions 41 are of the same width, and we will assume that under the 90 action of an actuating-lever a pinion is given sufficient rotation to move it laterally one-sixteenth of an inch. For one illustration we will assume that four candidates are represented for one office, to which but one may 95 be elected. The group at the top in Fig. 4 is set to provide for this condition, and it is evident that when any one of the actuators of that group is moved from its normal position indicated in Fig. 1 into its position indicated in Fig. 2 its gear will be moved laterally on the coöperating hub far enough to press the upper and lower pinions of that group into engagement with the stop-washers 42, which are rigidly held by the coöperating stop-brackets 43. When this expanding movement has taken place, it is evident that no other pinion of that group can be moved, since the limit of expansion or separation of the wheels 41 and hubs 40 of the 100 group is then reached, and hence that all the other actuators of the group will then be locked in normal positions. The intermediate group (illustrated in Fig. 4) comprises eight pinions, and the stop-brackets 43, which 105 embrace the group, are so spaced as to permit the group to expand or separate approximately one-eighth of an inch, or, in other words, to expand or separate enough to permit the rotation of two pinions 41 under the 110 action of the actuating-levers. This group is properly set for an office to which two candidates may be elected and for which there are eight candidates represented, counting the "independent candidate" one. As is 115 evident, any two actuators of this particular group may be operated either in succession or at the same time and that when two of the actuators have been set the other members of the group will be locked in their normal 120 positions, since such two movements expand or separate the pinions of that group to their limit.

Normally the segmental ends of the actu-

ating-levers 3 are placed against a stop-strip 53, which is adjustably secured on the guide-plate 49 by slot-and-screw engagements 54. When the stop-strip 53 is loosened up and 5 thrown forward to its limit, the segments 5 are all carried out of mesh with their coöperating pinions 41. This is important, as when the pinions are thus disengaged they may be properly adjusted and assembled into 10 groups.

The straight-vote-controlling device herein used is shown and broadly claimed in my said prior patent, No. 688,534, and hence may here be briefly described. It is best illustrated in 15 Figs. 1, 2, and 7, but also in Fig. 3. The three upper register-actuators and coöperating registers are shown as appropriated, respectively, to straight Republican, straight Democratic, and straight Prohibition tickets. 20 The straight-vote stop-blade, made up of the sections 55 and 56, is hinged on a vertical rod 57 and connected for reverse rocking movements by a short lever 58, pivoted at 59. The blade-sections 55 extend for coöperation 25 with the shoulders 7 of the three actuating-levers which are appropriated to straight votes, while the blade-section 56 extends for coöperation with the shoulders 7 of all of the individual-vote-actuating levers. Normally 30 the blades 55 and 56 stand as indicated by full lines in Fig. 1. When, however, one of the actuating-levers appropriated to straight votes, for instance, is moved, the blade-section 56 will be thrown in front of the shoulders 35 7 of all of the actuating-levers appropriated to individual votes. Of course when one of the individual-vote actuators is moved a reverse movement of the blades 55 56 will take place and all of the straight-vote actuators 40 45 will be locked. When one of the said blade-sections is moved rearward, the other will be moved forward, as indicated by dotted lines in Fig. 1.

I have also shown means whereby the so-called "independent votes"—that is, votes for parties not represented on the ticket—may be cast and the casting of such vote made to count as one vote against the voter. This device, briefly described, is as follows:

50 The numeral 60 indicates a long lever the free end of which normally closes a slot 61, (indicated by dotted lines in Fig. 1,) which slot may be assumed to open into a suitable receptacle. (Not shown.) Said lever 60 ex- 55 tends below the frame 1 and is secured to the depending plunger or shaft of an oscillating blade 62, which blade is mounted on a pair of levers 63, one at the top and the other at the bottom of the frame 1. At one end said 60 levers 63 are pivoted to brackets 64 in the frame 1, and at their free ends they are connected by links 65 to the arms 29 of the rock-shaft 25. The blade 62 is yieldingly held by a spring 66 against a fixed stop 67. On the 65 blades 62 are secured a plurality of detachable and adjustable stop-blocks 68, which co-operate with the shoulders 8 of the actuating-

levers 3. These blocks 68 are secured for coöperation only with those actuating-levers which are appropriated to independent votes. 70 As indicated in the drawings, the first block 68 from the top is applied for coöperation with the actuating-lever which is the seventh from the top. These blocks 68 may, of course, be readjusted and applied, so as to 75 bring them always in line with the independent-vote-actuating levers.

The operation of the machine, briefly summarized, is substantially as follows: The parts normally stand as indicated in Fig. 1. The voter in manipulating the register-actuating levers moves the same from their normal positions into their set positions, (indicated in Fig. 2,) and the number of register-actuating levers of a particular group which may be 80 set will be limited, as already described, by the so-called "limiting-lock" or "vote-limiting" mechanism involving the sliding screw-threaded hubs 40 and pinions 41. It may be here noted that the points of the beveled ends 85 or noses 11 of the latches 9 are set rearward or to one side of its center, so that it requires more than one-half of the possible movement of an actuating-lever to throw the same past the cam-rod 12. Hence it follows that if in 90 a group where but one vote may be cast for the office represented two actuators should be moved simultaneously, they could be given but half movements and upon being released would be thrown back to their normal positions by the spring-pressed latches 9. Even if one of the actuating-levers could be set in 95 any position short of the extreme position indicated in Fig. 2, it would not upon being returned with the other and properly-set actuators cause a vote to be registered, inasmuch as the tooth 17 of its pawl 16 would not have been thrown far enough to properly engage the ratchet 15 of the coöperating register. 100 When the particular actuator which is appropriated to the independent vote is moved, its lug 8 engages the coöperating block 68, rocks the blades 62 and long arms 60, and thereby opens the slot 61 and permits a ticket or check having marked thereon the name of 105 a candidate to be deposited through the slot 6 and into the receptacle which is to receive the same. When the said actuating-lever reaches its set position, the said block 68, blades 62, and long arms 60 are permitted to 110 fly back into their normal positions under the actions of the springs 66. After the voter has set all of the actuators which he is entitled to use and which it is possible for him to use, he takes hold of the handpiece 31 of 115 the plunger 30 and by drawing thereon causes the following actions to take place, to wit: First, the restoring-blade 24 is moved from its normal position into engagement with the forward inclines of the beveled ends or noses 120 11 of the latches 9 of the set of actuators. This same initial movement of said plunger 30 moves the eccentric 19 far enough to carry the toothed ends 17 of the pawls 16 laterally 125 130

inward or rearward in proper line for engagement with the ratchet-teeth 15 of the coöperating registers. Then by continued movement of said plunger 30 the said restoring-blade 24, working with a cam action on the beveled ends or noses 11, positively forces said actuating-lever back into the normal positions indicated in Fig. 1. This final movement of the actuating-levers causes the pawl 16 to operate their respective registers. The initial movement of the restoring-bar 24, acting through the arms 29, links 65, and levers 63, carries the block 68 rearward out of the path of the lugs 8 of the actuating-levers 3, and thus permits those actuating-levers which are appropriated to independent votes to be freely returned with the other levers under the continued movement of the said restoring-blade. When one of the actuating-levers appropriated to independent votes is moved into its set position, as previously described, it is temporarily locked against return movement—that is, is locked against return movement until released, as just indicated above. When the plunger 30 is drawn inward to its extreme limit, the restoring-blade 24 stands as indicated by dotted lines in Fig. 1 and locks all of the actuating-levers in their normal positions. Furthermore, at this time the lock-lugs 35 on the plunger 32 engages the shoulder of the slot 33 and locks the said restoring-blade in its said locking position. Hence the voter after he has cast his votes cannot reset the machine and the next voter cannot cast his vote until after the parts have been restored to their normal positions by an attendant or other person, who may so reset the machine by pulling on the plunger 32.

40 This voting-machine will usually be used in connection with a booth, in which case of course the plunger 30 will project into the booth, and the plunger 32 will project outside of the booth, where it cannot be reached by the voter from within the booth. It will also be understood that a machine such as described may be arranged in duplicate, triplicate, or quadruplicate, so as to provide for the voting of anyone or more of the national, 45 State, county, or municipal tickets.

50 The so-called "spring-latches" 9 not only serve to yieldingly hold the actuating-levers either in normal or set positions, but further serve as propelling devices to induce complete movements of said levers.

55 From what has been above said it will be understood that the so-called "limiting-lock" or "vote-limiting" mechanism is capable of many modifications. For instance, the elements corresponding to the so-called "sliding" hub and pinions might be moved laterally by a cam action other than that caused by screw-threaded engagement, and the connections between the actuating-levers and 60 the pinions or nut members might be made by other devices than gear-teeth. However, the wide-faced pinions, the screw-threaded

hubs, and the relatively thin or narrow segments give a construction which has important advantages over any other constructions 70 for the same purpose. The so-called "actuating levers or keys" may also take various forms. If desired, rollers might be applied to the so-called "cam-rod" 12 to reduce the friction between the same and the cam-noses 75 11 of the spring-latches 9. Other modifications as to details of construction may also be made within the scope of my invention as herein set forth and claimed.

What I claim, and desire to secure by Letters Patent of the United States, is as follows:

1. The combination with a group of registers and register-actuators, of vote-limiting mechanism comprising a series of laterally-expandable rotary elements, rotated one by each actuator and arranged to expand or spread laterally when rotated, and adjustable stops adapted to be interposed between any of the said elements, for limiting the expanding movements thereof and thereby limiting the 90 number of votes which may be registered, and also rendering variable the number of elements comprised in the group, substantially as described.

2. The combination with a group of registers 95 and register-actuators, of a vote-limiting mechanism comprising a group of shiftable non-rotary hubs located side by side, nut members screw-threaded on said hubs and adapted to spread or separate when rotated, 100 said actuators operating one upon each of said nut members, and stops limiting the spreading movements of the said nut members, to thereby limit the number of votes which may be registered, substantially as de- 105 scribed.

3. The combination with a group of registers and register-actuators, of a vote-limiting mechanism comprising a group of shiftable non-rotary hubs located side by side, pinions 110 screw-threaded on said hubs and adapted to spread or separate when rotated, said actuators having teeth for operation on said pinions, and stops limiting the spreading movements of said pinions and hubs, to thereby 115 limit the number of votes which may be registered, substantially as described.

4. The combination with a group of registers and register-actuators, of a vote-limiting mechanism comprising a group of shiftable 120 non-rotary hubs located side by side, nuts screw-threaded on said hubs and rotated, one by each of said actuators, washers interposed between said nuts and adapted to slide therewith, other washers embracing said group of 125 pinions, and adjustable stops for engaging and holding said outer washers against shifting movements, to thereby limit the spreading movements of the pinions of the said group, substantially as described.

5. The combination with a group of registers and register-actuators, of a vote-limiting mechanism comprising a non-rotary shaft, a series of screw-threaded hubs slidable on said

shaft but held against rotation thereon, nuts screw-threaded on said hubs and arranged to be rotated one by each of said actuators, and adjustable stops for limiting the spreading movements of said hubs and nuts and thereby limiting the number of votes which may be registered, substantially as described.

6. The combination with a group of registers, of a corresponding group of pivoted register-actuating levers having toothed segments and register-actuating pawls, and a vote-limiting mechanism comprising a non-rotary shaft, a series of non-rotary hubs slidable on said shaft, pinions screw-threaded on 15 said hubs and meshing one with the segment of each of said actuating-levers, and stops limiting the spreading movements of said pinions and hubs and thereby limiting the number of votes which may be registered, substantially as described.

7. The combination with a group of registers and register-actuators, of a vote-limiting mechanism comprising a non-rotary shaft, a group of non-rotary hubs slidable on said 25 shaft, nuts screw-threaded on said hub and operated one by each of said actuators, washers interposed between said nuts, and the adjustable stop-brackets pronged and grooved to embrace the outer members of said washers, to thereby hold the same against lateral movements and to thereby limit the spreading movements of the nuts of the group, substantially as described.

8. The combination with a group of registers 35 of a corresponding group of pivoted register-actuating levers having toothed segments and register-actuating pawls, and a vote-limiting mechanism comprising a non-rotary shaft, a series of non-rotary hubs slidable on 40 said shaft, a series of pinions screw-threaded one on each hub and meshing one with the segment of each actuating-lever, washers interposed between said pinions, and pronged stop-brackets grooved to engage the outer 45 members of said washers, to thereby anchor the same and limit the spreading movements of the said pinions, substantially as described.

9. The combination with a group of registers and register-actuating levers or keys, of devices applied to said levers for insuring and 50 completing full movements thereof, which devices act on said levers throughout their movements from one extreme position to the other, substantially as described.

55 10. The combination with a group of registers, of a corresponding group of pivoted register-actuating levers, spring-pressed latches mounted on said levers and provided with V-shaped cam-noses, and a cam-rod with which 60 the noses of said latches engage throughout the movements of said levers, to yieldingly hold said levers in extreme positions and to insure complete movements thereof, substantially as described.

65 11. The combination with several groups of registers and pivoted register-actuating le-

vers, of limiting lock mechanisms controlling the several groups of actuators, one group of said actuators being appropriated to straight votes and the others to individual votes, and 70 a lock-blade formed in two sections and so arranged that when one of the straight-vote actuators is moved, the individual-vote actuators are locked, and vice versa, substantially as described.

75 12. The combination with a group of registers, of a corresponding group of pivoted register-actuating levers adapted to be moved individually to and from operative positions without action on said registers, and an oscillating restoring-blade for rocking said levers on their pivots, to thereby render the same operative on their respective registers and to restore said levers to their normal positions, substantially as described.

80 13. The combination with a group of registers and coöperating pivoted register-actuating levers, said levers carrying projecting inclined cam-surfaces, of a restoring blade or bar for action on said cam-surfaces, to restore 85 said actuating-levers to their normal positions, substantially as described.

85 14. The combination with a group of registers and register-actuating levers, of register-engaging pawls pivoted to said levers, a lever-restoring blade or bar for moving said levers back to normal positions, and connections whereby the initial movement of said restoring-bar moves said pawls into operative 90 positions, substantially as described.

95 15. The combination with a group of registers and register-actuating levers, of register-engaging pawls pivoted to said levers, an eccentric device for moving said pawls into and out of operative positions, and a lever-restoring blade or bar having connections to said eccentric device, whereby, under the movement of said restoring-blade, said pawls are first thrown into operative positions and are 100 subsequently caused to actuate their respective registers under the return movements of said levers effected by said restoring-blade, substantially as described.

105 16. The combination with a group of registers, of the corresponding group of pivoted register-actuating levers having toothed segments, a vote-limiting mechanism involving pinions meshing with said segments and movable laterally when rotated, stops limiting the spreading movement of said pinions, and a 110 stop device for said levers normally holding the segments thereof in mesh with said pinions, but moving to permit the throwing of said segments out of mesh with said pinions, to permit the said pinions to be readjusted, 115 substantially as described.

In testimony whereof I affix my signature in presence of two witnesses.

SYVER LOE.
